UNITED STATES PATENT OFFICE

171,606

COMBINED COOKY DISPLAY AND DISPENSING CASE

Robert H. MacAleese, Indianapolis, Ind., assignor to Syndicate Glass, Inc., Indianapolis, Ind., a corporation of Indiana

Application August 3, 1953, Serial No. 26,252

Term of patent 14 years

(Cl. D80—11)

To all whom it may concern:

Be it known that I, Robert H. MacAleese, have invented a new, original, and ornamental Design for a Combined Cooky Display and Dispensing Case, of which the following is a specification, reference being had to the accompanying drawings, forming a part hereof.

Fig. 1 is a front perspective view of a combined cooky display and dispensing case showing my new design.

Fig. 2 is a rear perspective view.

Fig. 3 is a side elevational view.

Fig. 4 is a top plan view.

I claim:

The ornamental design for a combined cooky display and dispensing case, substantially as shown.

ROBERT H. MACALEESE.
